E. D. BROOKER

HAEMOCYTOMETER AND METHOD OF MAKING THE SAME

Filed Jan. 2, 1923

Inventor
Eugene D. Brookner
By his Attorney
Charles G. Hensley

UNITED STATES PATENT OFFICE.

EUGENE D. BROOKER, OF NEW YORK, N. Y.

HÆMOCYTOMETER AND METHOD OF MAKING THE SAME.

Application filed January 2, 1923. Serial No. 610,219.

To all whom it may concern:

Be it known that I, EUGENE D. BROOKER, a citizen of the United States, and a resident of the city, county, and State of New York, have invented certain new and useful Improvements in Hæmocytometers and Methods of Making the Same, of which the following is a specification.

My invention relates to hæmocytometers or instruments used for making corpuscle counts of the blood, for making bacteria counts, and for similar purposes. Heretofore, these instruments have usually been made of glass and comprised a base, a central table and side tables at each side thereof, the side tables rising one tenth millimeter above the plane of the center table so that when the slide is placed on the tables there will be a space between the under surface of the slide and the top surface of the central table of one tenth millimeter in depth to form the counting chamber. Cross lines are generally placed on the center table within which the number of corpuscles or bacteria are counted under a microscope. There are gutters formed between the several tables and sometimes across the central table, in which any excess fluid under test may run off without reaching the top surfaces of the side tables. Heretofore, these instruments have been made in two general ways. One has been to make the base and the tables separately and to then cement the tables in place on the base with Canada balsam. The objection to this method has been that the liquids used for cleaning the instruments often dissolved the balsam and loosened the tables, or sometimes a knock or jar loosened the tables, either detaching them entirely or loosening them enough to destroy the accuracy of the instrument. The other method has been to mill out a solid block of glass to form the tables and gutters; and the objection to this method is that of expense although the instrument is otherwise superior to those made under the first method.

The object of my invention is to provide a hæmocytometer having the perma-

nency or ruggedness of those made under the last described method but which may be produced at a much lower cost, in fact at a cost nearly as low as those made under the cementing process. My invention therefore relates to the method of making these instruments and to the product produced under this method.

In the drawing forming part of this application,

Figure 1 is a sectional view of a hæmocytometer embodying my invention in one of its forms,

Figures 2 and 3 are similar views showing my invention in other forms, and

Figure 4 is a plan view of all the several forms.

In the practice of the method of making my improved hæmocytometer I provide a base which is suitably ground off on its faces, and which base is preferably of harder glass than that of which the tables are made; and on this base one or more of the tables are attached permanently by fusing the table to the base. If the table is made of softer glass than the base and these are subjected to fusing heat the table will soften quicker than the base and fusion will take place without distortion of the base. In one form of my invention I fuse a relatively thick table to the base and then grind down the tables to the desired thickness because if a very thin table member were subjected to the fusing heat it would warp too much; whereas, if it is thick this will not occur; and the grinding down also removes any irregularity in the table. In another form I employ relatively thick tables and seat them in channels in the base and then fuse them to the base. But in all cases I fuse some or all of the tables to the base. This makes the base and table practically one piece so that the use of acids or solvents will not loosen or separate the table and base, nor will shocks.

Referring first to the construction shown in Figure 1 where the instrument is shown on an enlarged scale, there is a base 1 of glass consisting of a flat plate ground par-

allel on its opposite surfaces 2, 3. On this base I have mounted three tables comprising a center table 4 on which a single or double counting scale or cross-line marking 5 is provided on its top surface; and the two side tables 6, 7. The side tables as originally formed are thicker than their final form, as is indicated by the dotted lines 8, 9, in order that these tables will not 10 warp to any great extent when subjected to fusing heat. These side tables are spaced laterally apart as shown and parallel to each other upon the base 1 and the base with these tables resting thereon are subjected to 15 just sufficient heat to cause the tables and base to fuse and form an integral body.

In this form of any invention the center table 4, after the base and side tables have been annealed, is placed upon the base and is 20 attached thereto by cement or Canada balsam. The center table is so placed as to leave gutters 10, 11 between it and the side tables for excess liquid under test to flow off from the counting chamber. The side 25 tables 6, 7 are then ground down on their top surfaces and polished, removing the material indicated by the dotted lines 8, 9 until the top surfaces 12 of these tables are slightly above the plane of the top 13 of the 30 central table 4. Then if an ordinary slip or slide (not shown) is placed upon the side tables 6, 7 there will be a slight space, generally one tenth millimeter, between the center table surface 13 and the under surface of 35 the slide, forming the counting chamber to be occupied by the blood or other fluid under test. As the center table lies between the side tables 6, 7 it is more or less protected against displacement from a blow 40 by them. The construction is superior to one in which all the tables are cemented to the base although inferior in some respects to some of the other forms to be described.

In Figure 2 I have shown a device in 45 which none of the three tables is cemented. In this construction I first provide a base 1 which is somewhat thicker than the final base is to be and the base is then ground or otherwise treated to remove the portions 50 shown by dotted line 14. This will leave the final base with a central raised member 15 integral therewith to constitute the central table. The side tables 16, 17 of greater thickness than is ultimately required, are 55 placed upon the base in spaced, parallel relation, as shown, to form gutters 10, 11 between them and these side tables are then fused to the base by being subjected to sufficient heat to fuse these parts together.

60 The portions of these side tables represented in the dotted lines 18 are then ground off to reduce the tops of these tables to a plane slightly above the plane of the center table 15. In the finished article the base 65 and all tables will be integral.

In the construction shown in Figure 3 a relatively thick base 1 is milled or ground out to provide cross recesses 19, 20 sufficiently wide to form the gutters 10, 11 and sockets for the side tables. This milling or 70 grinding leaves a center table 21 between the ground out recesses or channels 19, 20. The blocks 22, 23 for the side tables are then placed in the recesses 20, 19 and spaced from the center table to form the gutters 10, 11 75 and then the side tables and base are fused to make them integral. The side tables are then ground down to remove the portions shown in dotted lines 24 leaving the top surfaces just above the plane of the top surface of the center table 21. In this construction all tables become integral with the base.

In Figure 4 it will be seen that the top appearance of all forms may be the same 80 and I prefer to run the several tables out to the full width of the base and then grind the edges 31, 32 of the base and the ends of the several tables off even at one time. In all forms the center table may have a single 85 set of cross lines 5 or, in accordance with common practice the center table may have two sets of cross lines as indicated by dotted lines 33, 34 and the center table may have the two gutters 35, 36 cut crosswise there- 90 through as indicated by dotted lines. In the latter form, separate specimens may be examined under each set of cross lines and the gutters 35, 36 will prevent one speci- 95 men from flowing into the other across the center table. This conforms to present 100 practice.

Having described my invention what I claim is:

1. The method of making haemocytometers, which consists of providing a base, placing thereon blocks or strips to form tables for the purpose set forth, and in fusing said base and said table members together in an integral construction.

2. The method of making haemocytometers having a central table and side tables, which consists in providing a base with a center table, in placing relatively thick blocks or strips on said base, in fusing said base and said blocks together in an integral mass and in then considerably reducing the height of said blocks by removing material from the tops thereof for the purpose set forth.

3. A haemocytometer comprising a base and tables projecting above said base, said tables being formed of separate blocks of material united with said base by fusing the base and blocks together in an integral body.

4. A haemocytometer comprising a base having portions thereof removed to leave an integral center table projecting above the base, and side tables spaced from said cen- 130

ter table and formed by blocks fused to said base.

5. A haemocytometer comprising a base having spaced recesses formed therein to leave an intermediate projection forming a center table, and side tables spaced from said center table and formed by blocks in-

serted in said recesses and each having a plurality of sides fused to the base at the side walls of said recesses.

Signed at the city, county and State of New York, this 22nd day of November 1922.

EUGENE D. BROOKER.
